UNITED STATES PATENT OFFICE.

SANFORD L. CLUETT, OF TROY, NEW YORK, ASSIGNOR TO CLUETT, PEABODY & CO., INC., OF TROY, NEW YORK, A CORPORATION OF NEW YORK.

HINGED CONNECTION FOR FOLDER BARS.

Application filed October 21, 1921. Serial No. 509,382.

To all whom it may concern:

Be it known that I, SANFORD L. CLUETT, a citizen of the United States of America, and resident of Troy, in the county of Rensselaer and State of New York, have invented new and useful Improvements in Hinged Connections for Folder Bars, of which the following is a specification.

This invention concerns folding and 10 pressing machines and relates more particularly to machines of this character such as are especially adapted for the folding and pressing of collar and cuff blanks.

In machines of this type it is common to 15 employ two pairs of oppositely disposed folder blocks upon which the folder plates are mounted. Corresponding blocks of each pair are normally arranged in alignment, but with their adjacent ends in spaced relation. During the folding operation, the 20 blocks of each pair are caused to sweep inwardly toward each other in arcuate paths, the ends of the corresponding blocks of the two pairs thus approaching one another. During such movement all of the blocks 25 must be maintained in substantial parallelism to their original positions; and for imparting the desired movement thereto it has been common to connect each end of 30 each block to a crank or eccentric, and to provide for the simultaneous rotation of all of such cranks or eccentrics. This entails an undesirable complexity of driving connection and to simplify the machine it has 35 been proposed to dispense with the eccentric or crank drive at the adjacent or inner ends of the several blocks and to connect the ends of corresponding bars of the two pairs by means of a slide member seated in longitudinal 40 grooves in such blocks. While from a theoretical standpoint the latter arrangement might seem desirable, practical considerations prevent it from being an unqualified success. In the first place, the cutting of 45 longitudinal slots in the blocks very materially weakens them so that when subjected to the upward pressure of the bed plate they are liable to crack or break. The cutting of the slot and the machining of the slide bar

the presser blocks, it is subject to binding 55 within its slot under the varying effects of pressure and temperature to which it is constantly subjected. Furthermore, in order to maintain the slide in working condition it is necessary to oil it freely and in the operation of the machine the oil is frequently spattered upon or otherwise brought into contact with the material being operated upon, thus resulting in damage and loss.

The object of the present invention is to 60 improve a machine of the class above referred to and particularly to provide for connecting the adjacent ends of aligned presser blocks in such manner as to permit of the proper relative movements thereof 65 while at the same time avoiding the disadvantages inherent in the employment of a slide bar for connecting such parts. With this object in view the invention may consist briefly in connecting adjacent ends of 70 aligned presser bars by hinge means of a character such as to maintain such bars in alignment at all times while at the same time permitting the ends of such bars to approach or recede as occasion may require. 75 Preferably the connecting means employed may comprise a broad leaf-hinge of substantially usual form, having its leaves hingedly secured to adjacent ends of the respective presser bars. This arrangement may 80 readily be applied to the machine without necessitating expensive machining operations and without weakening the presser bars to any substantial extent. The functioning of such a connection is not appreciably affected by temperature changes or 85 presser variations while the employment of pivotal connections between the parts lessens mutual wear and the necessity for lubrication, and at the same time facilitating 90 and cheapening any necessary replacements due to accidental injury or long continued use.

A preferred arrangement, exemplifying means suitable for carrying the invention 100 into effect is illustrated in the accompanying drawings in which,—

Fig. 1 is a fragmentary end elevation of a machine having the present improvements applied thereto;

Fig. 2 is a front elevation, partly broken away, of the machine shown in Fig. 1;

Fig. 3 is a plan view of the machine, the

105

parts being shown in the position which they occupy at the beginning of the folding operation;

Fig. 4 is a view similar to Fig. 3, but with certain parts broken away and illustrating the position of the folder members at the completion of the folding operation;

Fig. 5 is a transverse cross section to large scale taken on the line *a*—*b* of Fig. 3; and

Fig. 6 is a longitudinal vertical cross section on the line such as *c*—*d* of Fig. 5.

The machine herein illustrated is in general of well known construction comprising the table 1 supported upon the leg members 2. This table is provided with a central, longitudinal opening within which is arranged the bed plate 3 which constitutes one of the cooperating presser elements. This bed plate as herein shown is provided with cavities 4 for the reception of electrical heating coils and may be raised and lowered during the pressing operation by any suitable mechanism, such for example as the pneumatically actuated piston disclosed in the patent to Brown, No. 1,053,477, February 18, 1913. Secured to the rear portion of the machine frame is a bracket 5 to which is pivoted the die arm 6. Mounted upon the free end of this arm is the die 7 which constitutes the other of the presser elements. The arm 6 with its die may be brought down into cooperative relationship to the bed plate 3 by any usual and well known mechanism or device, such for example as that shown in the patent to Brown, above noted, but not herein disclosed.

Mounted upon the upper surface of the table and movable in planes substantially parallel thereto are the folder blocks 8, 9, 10 and 11, such blocks being arranged in pairs for cooperation in the folding operation, the corresponding blocks of each pair, as for example, the blocks 8, 10, 9, 11, being arranged to extend in alignment with one another. The block 8 has secured thereto a bracket 12, similar brackets 13, 14, 15 being secured to the blocks 9, 10 and 11 respectively. These brackets are pivotally mounted upon crank pins 16, 17, 18, 19, respectively, carried at the upper ends of shafts rotatable in suitable bearings carried by the machine frame. These shafts are provided with crank arms at their lower ends and connected to each of the cranks, 55 is a connecting rod, the front connecting rods 20 being secured to a common cross head 22 secured to a piston 23. In a similar manner the rear pair of connecting rods are connected to a cross head, not shown, secured to a piston rod also not shown. The piston rod 23 is provided with a piston at each end movable in cylinders 24, 25, respectively, as more fully described and illustrated in the patent to Brown above noted. These cylinders may be connected

through suitable valve mechanism with a source of pressure fluid, whereby the pistons therein may be actuated to cause movement of the rods 20 and thereby rotation of the discs with their pins. Such movement serves to impart bodily movement of rotation in opposite directions to the remote ends of the blocks 8, 10, and the blocks 9, 11 respectively, the ends of the blocks 9 and 10 moving in a clockwise direction, while the ends of the blocks 8 and 11 move in a counter-clockwise direction. For holding the blocks downwardly in parallelism with the table when subjected to the upward thrust of the bed plate, suitable hold-down members as 26, 27 are provided, such members being mounted on the table 1 and bearing upon the upper surfaces of the respective blocks.

Secured to each of the blocks is a folder plate or blade such as 28, such plate being of relatively thin material, suitable for engagement with the material in folding the same. As the folder blocks are actuated only by connections engaging their remote extremities, it is necessary to provide connecting means for their adjacent extremities of such a character as to maintain the blocks 8, 10, 9, 11, respectively in alignment during their inward operative movement. For this purpose adjacent ends of the several blocks are provided with bracket members 29, suitably secured thereto. Projecting upwardly from each of the bracket members are spaced ears having aligned openings in which are arranged pivot pins 32. Pivotally mounted upon the respective pivot pins are leaf members 33, 33^a constituting the elements of a leaf hinge. The free extremities of such leaf members are pivotally connected by means of a pin 34. The leaf hinges which thus serve to connect the adjacent ends of aligned blocks are relatively wide in a direction transverse of the length of such blocks, and thus constitute substantially rigid connections in so far as movement in a direction transverse to the axes of the blocks and in a plane parallel to the table, is concerned. Such hinge connection, however, is collapsible in a direction perpendicular to the surface of the table, thus permitting the adjacent ends of the blocks to approach one another during the movement imparted to them by their respective crank pins. This hinge connection therefore serves to maintain the blocks in alignment at all times while at the same time permitting them to take up the desired motions during the folding operation. While as herein disclosed a leaf hinge has been illustrated as suitable for connecting the adjacent ends of the folder blocks, it is contemplated that under some circumstances other means comprising pivotal connections might be substituted for such hinge pro-

vided such means were so constructed as to insure transverse rigidity in the plane parallel to the table while providing flexibility or ability to collapse in a direction perpendicular thereto. Furthermore, while the invention has been shown as applied to a specific form of folding machine, it is to be understood that its application to machines of other types is contemplated as falling 10 within the scope of the invention.

Having thus described the invention in a preferred embodiment of the same together with the mode of operation thereof, what I claim and desire to secure by Letters Patent 15 of the United States is:

1. A folding machine comprising a pair of bodily movable folder blocks and means movable with said blocks and comprising pivotal connections for uniting adjacent 20 ends of said blocks the axes of turning of said pivotal connections being substantially parallel to the plane of the blocks.

2. A folding machine comprising a pair of elongate folder blocks, means connected 25 to the remote ends of the respective blocks for imparting bodily movement thereto, and means comprising pivotal connections for uniting the adjacent ends of the blocks to one another.

3. A folding machine having normally spaced, folder blocks, and foldable connecting means having elements pivotally connected to the respective blocks.

4. A folding machine comprising aligned 35 folder blocks, members having pivotal connection with adjacent ends of the respective blocks, and means for pivotally connecting said members.

5. A folding machine comprising aligned 40 and normally spaced folder blocks, and hinge means connecting adjacent ends of said blocks.

6. A folding machine having spaced folder blocks, a hinge comprising pivotally con-

nected leaves, and hinge means for connecting one leaf to each of the blocks. 45

7. A folding machine having spaced folder blocks, a support secured to the end portion of each block, a pair of spaced ears carried by each of said supports, a leaf 50 member having one of its ends pivotally mounted between each pair of ears, and a pivot pin for connecting the free ends of said leaves.

8. A folding machine comprising a pair 55 of aligned folder blocks, means having operative connection with the remote ends of said blocks for imparting simultaneous movement of rotation in a common plane and in opposite directions to said ends, and 60 means for connecting adjacent ends of said blocks, said means being substantially rigid in a direction parallel to the plane of movement of said blocks but flexible in a direction perpendicular thereto. 65

9. A folding machine comprising a pair of aligned, elongated folder blocks, means for simultaneously moving the remote ends of said blocks in arcuate paths, and means for connecting adjacent ends of said blocks, 70 said connecting means being substantially rigid in a direction perpendicular to the axes of said blocks, and yieldable in a direction perpendicular to the plane of rotation of said ends. 75

10. A folding machine comprising a pair of aligned, elongated folder blocks, means for imparting opposite movement of rotation to the remote ends of said blocks, supports secured to adjacent ends of the respective blocks, a wide leaf hinge comprising pivotally connected leaves, and hinge connections between said leaves and the respective supports. 80
